MOLDING PRESS

Major E. Gates, Crystal Lake, Ill.

Application October 13, 1941, Serial No. 414,726

8 Claims. (Cl. 25—98)

This invention relates to the manufacture of pressed fire-brick and other pressed ceramic articles and, among other objects, aims to improve the quality of the product and to improve the efficiency of the apparatus and method of manufacture.

The nature of the invention may be readily understood by reference to one illustrative apparatus embodying the invention and shown in the accompanying drawings:

In said drawings:

Fig. 1 is a sectional elevation of the apparatus; Fig. 2 is a diagram showing successive crank positions represented in the diagram of Fig. 3;

Fig. 3 is a diagram illustrating successive toggle positions;

Fig. 4 is a diagram similar to Fig. 2;

Fig. 5 is a diagram similar to Fig. 3 illustrating another adjustment of the mechanism; and

Fig. 6 is a sectional elevation similar to that of Fig. 1, illustrating a different form of apparatus.

In the manufacture of fire-brick and similar refractory articles the quality of the product is improved by increase in intimacy or extent of contact between the clay particles. Use of high molding pressures for this purpose is limited, however, because of air present in the clay. Initially voids between the clay particles may be as high as 50% of the aggregate volume. To facilitate elimination of air, it has been the practice to apply suction to the mold during compression, but these practices have been only partially successful because even with application of suction it is difficult for all the air to escape, even when the clay is relatively dry. The air escapes until the clay has been compressed to within 5 to 10% of its final volume, after which the air escapes with difficulty and only very slowly. If all or substantially all of the air were removed from the clay, very much higher pressures than are now permissible could be used with the result that the quality of the brick would be greatly improved. Moreover, small internal flaws generally caused by subsequent expansion of air upon release of pressure would be absent.

The quality of the brick could be improved simply by allowing a longer time for the particles of clay to slide over each other into more intimate contact and for the residue of air to escape. This, however, is obviously impracticable since it would require that the apparatus be stopped during its cycle of operation while the clay was under pressure. In the illustrative apparatus, the quality of the brick is improved by

modifying the cycle of operations without reducing the speed of operation.

The invention is here shown embodied in a press similar to the well-known Boyd press. The details of a typical Boyd press are illustrated and described in Flood Patents Nos. 985,153 and 987,124. In the ordinary Boyd press, which is a toggle press, maximum pressure on the clay (which occurs substantially when the toggle arms 10 are in alignment or at dead center) is only momentary and even with the application of suction there is insufficient time in the cycle to allow for escape of air. The illustrative apparatus utilizes the principles of the Boyd toggle press but modifies the cycle of operation so that a very much longer portion of the cycle is devoted to applying high pressure to the clay and holding the same under high pressure for a period adequate to effect a much greater elimination of air. The illustrative press also is capable of very extensive variation in its cycle to adjust the cycle to the particular condition and qualities of the clay used. Only those details of the Boyd press mechanism as are involved in the illustrative apparatus are illustrated.

In general, the press comprises a mold 10 whose sides are stationary. The upper and lower faces 11 and 12 of the mold are movable relatively to each other and to the stationary sides of mold 10. The upper face is carried on a plunger 13 vertically slidable in guides in side bars 14 and connected to pairs of toggle arms 15 and 16. The latter are pivoted at their upper ends 17 to a cross-head 18 connected to the side bars 14. The lower face 12 of the mold is carried on a plunger 19, also vertically slidable in guides in the side bars 14 and adapted to seat on the saddle or cross-head 20 when the brick is being compressed. The cross-head extends between and is connected to the lower ends of side bars 14. In effect the mold space between the upper and lower faces 11 and 12 and the stationary sides moves with the relative movement of the upper and lower faces 11 and 12. As in the typical Boyd press, the entire assembly of plungers, toggle links and side bars is vertically slidable in stationary guides 21 in order to raise the brick out of the mold after it has been pressed to permit its discharge and then to lower the plunger 19 by a predetermined distance to receive the next charge of clay.

The toggle is operated by connecting rods 22 and crank 23. The drive for the crank is here shown in the form of a gear 24 connected to the crank shaft 25 and driven by pinion 26. The illustrative apparatus comprises only a

single mold located between pairs of toggle links and connecting rods. The regulation of pressures can be much more effective with a single mold than with the multiple mold of the typical Boyd press. Reciprocation of the toggle link assembly for discharge of the brick and filling the mold is effected as in the conventional Boyd press by means of the cam rollers 27 which serve as fulcrums for connecting rods 22 to raise and lower the mold at the proper time in the cycle. Generally the connecting rod has a cam surface 28 on its lower face so as appropriately to modify the action of the connecting rod in raising and lowering plunger 13. After final compression of the brick, the assembly is elevated (the toggle links opening to raise the plunger 13 above the brick) to bring the lower face of the mold flush with the upper surface 29 of the press table. The brick is then laterally shifted on to the table by the reciprocating hopper 31 whose forward end 32 acts as a plunger. Immediately thereafter plunger 12 is lowered by a predetermined distance while the hopper is located over the mold, and a charge of clay from the interior of the hopper fills the mold. Thereafter the hopper is retracted and the toggle arms are closed to compress the brick.

Adjustment of the amount of clay placed in the mold is effected by varying the elevation of the face 12 of the lower plunger at the time the charge is deposited therein. In the present case, as in the Boyd press, this is effected by constructing the plunger 19 to move vertically relative to the saddle or cross-head 20. The plunger is resiliently urged upwardly by spring 33. The position of its upper movement at the time of charging the mold is controlled by lever 34. Lever 34 is pivoted at 35 to a bracket 36. Its forward end 37 engages a stop 38 on rod 39 depending from the plunger. The other end of the lever is vertically adjusted by a screw 40. Adjusting screw 40 may be rotated manually as in the conventional Boyd press or automatically as here shown. The details of this automatic adjustment are disclosed in my copending application, Serial No. 307,427. A description of such details is not necessary for present purposes.

Spring 33 functions also to effect some pre-compression of the clay under relatively light pressures, 100 pounds or less per square inch, during the movement of the lower plunger 19 against the saddle 20. While this precompression serves to eliminate some air, the physical limitations on the spring prevent development of pressures high enough to be substantially effective for this purpose.

The inner bearings 45 and 46 of the respective pairs of toggle links are not coaxial as in the conventional Boyd press but are connected by an intermediate link 47, in this case integral with connecting rod 22. This intermediate link in conjunction with the movement of the connecting rod permits a very substantial alteration of the typical pressure cycle of the Boyd press and makes it possible, among many variations, to prolong the maximum pressures exerted on the clay for a very substantial portion of the cycle. Because of the very slight longitudinal movement of the toggles as they approach alignment or "dead center," it is difficult to illustrate by conventional means what takes place, particularly as regards the pressure pattern or cycle. Even such a slight movement as .001" has a very pronounced effect on the pressures which reach the neighborhood of 5,000 or 6,000 pounds per

square inch. However, the principle of prolongation of maximum pressures or modification of the conventional toggle pressure pattern may be readily grasped by noting that oscillation of the intermediate link 47 even without longitudinal movement of the connecting rod would produce very marked changes in the pressure exerted by the toggle where, as above pointed out, slight movements such as .001" are material.

For example, to prolong the application of high pressure on the brick without increasing the duration of the complete cycle, it is simply necessary to oscillate link 47 during the period when the toggle arms are in the region of alignment and at the same time to carry the toggle arms through or past their dead center.

In Figs. 2 and 3, one set of conditions is illustrated diagrammatically. Figure 3 represents nine successive positions of the toggle arms, the intermediate link 47, and the crank when the toggle arms are in the region of alignment or near alignment, i. e. where high pressures are being exerted. The respective positions are correspondingly numbered on the crank circle from 0 to 8. The toggle dead center is represented by the dot and dash line DC, connecting the upper and lower bearings of the toggle. For simplification and to permit illustration on a larger scale, only the position of the intermediate link 47 and its relation to toggle dead center is illustrated, the connecting rod and main toggle links having been omitted; the corresponding positions have been shown on the crank circle in Fig. 2. Also incorporated in the diagram is a pressure chart showing the pressure pattern or the relative pressures developed at successive positions of the toggle and link. The chart is, of course, fragmentary, embracing only the high compression zone.

In the diagram of Fig. 3, the link 47 is 3° out of perpendicular with the connecting rod 22, its lower arm being at an angle of 87° to the connecting rod. Adjustment of the link relative to the connecting rod and to the toggle links is effected in this instance by employing eccentric bushings 48 and 49 at the respective toggle connections. It will be apparent that relative rotation of these eccentric bushings will shift the pivot centers of the intermediate link relative to the connecting rod and thereby permitting such adjustment as may be necessary under varying conditions. Also for purposes of adjustment the connecting rod bearings 23 are provided with means in the form of eccentric bushings 50 which will permit adjustment in the position of link 47 relative to the dead center line. The character of the pressure pattern depends in part on the displacement of link 47 from "dead center" while it approaches and passes parallelism with the toggle "dead center" line.

In both diagrams of Figs. 3 and 5, the successive positions 0 to 8, inclusive, represent (as shown in Figs. 2 and 4) increments of 5° in a crank angle beginning with 20° before "near" crank dead center and continuing to 20° past dead center. In the adjustment represented in Fig. 3, the bushing 50 is set so that the intermediate link 47 does not pass entirely through dead center. In positions 2, 3, 4 and 5, the lower portion of the intermediate link crosses the dead center line but the upper portion never passes through dead center. Although the intermediate link crosses the dead center line in the aforesaid positions, peak pressures are not developed because of the angle of the intermediate link relative to

the dead center line. Substantially higher pressures develop in position 7 where the intermediate link is substantially displaced from the dead center line but because it is substantially parallel thereto higher pressures develop. It will be noted that the peak pressure does not occur (as in the conventional apparatus) at crank dead center, which in the present diagram is position 4, since in this position the intermediate link is not parallel to the dead center line but lies at an angle of 3° thereto. In the region of crank dead center, the intermediate link 47 swings at its highest rate but beginning with position 4 it simultaneously moves away from the dead center line, thus flattening out the pressure curve.

The pressure curve superposed on the diagram represents only relative pressures. Absolute pressures depend upon the volume of clay in the mold. Indicated on the diagram in inches are the successive displacements of the center of the intermediate link from the dead center line but these are significant only for the specific adjustment of crank bushing 50 and the dimensions of intermediate link, connecting rod, crank diameter and toggle links. In the illustrative apparatus, the intermediate link is 7" in length plus or minus the adjustment effected by the bushings 48 and 49. The connecting rod 22 is 48 1/2" in length. The crank circle is 13 1/2" in diameter and the toggle links 15 and 16 are 20" in length.

The diagram of Fig. 5 illustrates, particularly by comparison with that of Fig. 3, the effect of various adjustments on the toggle mechanism. This diagram illustrates the same successive crank positions as those of Fig. 3, namely, 5° increments for 20° on each side of "near" crank dead center but bushings 48 and 49 have been adjusted to change the effective angle between link 47 and connecting rod 22 to 90°30' instead of 93°, as in the diagram of Fig. 5. Also bushing 50 has been adjusted to shift the connecting rod and intermediate link 47 to the right as compared with the arrangement of Fig. 3 so that link 47 passes through the toggle dead center line before the high compression zone is reached. It will be noted that in position 0, link 47 is already substantially displaced to the right of the dead center line. This adjustment provides a pressure pattern in which the pressure in the intermediate portion of the zone has relaxed slightly. Following the region of relaxation, the pressure builds to a magnitude more than the previous maximum. This avoids any flaws which might otherwise be caused by expansion of occluded air in the intermediate portion of the high compression zone. This zone, it will be noted, extends somewhat beyond position 8, in which position the pressure is still rising.

The extent and duration of relaxed pressures in the high compression zone may be varied by the distance by which the intermediate link is carried through the toggle dead center position. The maximum displacement in the arrangement of Fig. 5 occurs in the region of position 4 and is approximately 3/4 of an inch. An increase in this distance would further relax the pressures and a decrease would minimize the relaxation. Whether or not relaxation in pressure during the high compression zone is desirable depends largely upon the character and condition of the clay.

It will be apparent from the foregoing, first, that the high compression zone can be extended over a substantially greater portion of the crank

cycle than has been possible with the conventional toggle link arrangement, thereby greatly increasing the opportunity for the particles of clay to slide on one another into more intimate relationship, resulting in a denser product and eliminating a greater amount of air; and, second, that almost an indefinite variation in pressure pattern is possible to meet varying conditions.

A somewhat different apparatus is illustrated in Fig. 6. As there shown, a hydraulic cylinder 60 and its plunger 61 are located below the lower mold plunger 12 and provide a means for protecting the brick against excessive pressures. The cylinder is controlled by an adjustable relief means set to yield when a predetermined maximum pressure has been applied to the brick. As stated above, the maximum pressure applied to the brick depends upon the amount of air remaining in the brick. So long as any air remains, there is always danger that high pressures will develop excessive compression in the minute amount of air remaining in the brick with the result that slight fissures and flaws will be caused. Hence, it is important that high pressures be controlled so as not to produce subsequent flaws. For each condition of clay, there is generally a different air residue in the brick, for which the maximum safe pressure must be appropriately adjusted.

The relief means is here shown in the form of a relief valve 62 connected through line 63 with the cylinder. The relief valve is held on its seat 64 by a piston 65 under predetermined air pressure applied through line 66. If and when the pressure on the brick exceeds a predetermined maximum, the valve 62 will be raised against the pressure of its piston 65 and a small amount of oil will escape from the cylinder through line 67 into storage tank 68.

To permit normal functioning of the mold plunger 12 at other times in the cycle, the pressure on the valve piston 65 is relieved by means of valve 69. Spring 70 below piston 65 then opens valve 62. The mold plunger 12 is resiliently elevated in this instance by air pressure on the oil in reservoir 68. This air pressure may advantageously apply greater force to the plunger than is possible with an ordinary spring like spring 33, and thus allow a very substantially higher precompression of the clay as the mold plunger is forced down to its bottom position, with the resultant greater elimination of air. When this position is reached, valve 62 is automatically closed (by operation of valve 69) and air pressure is placed on piston 65 to prevent further downward movement of the mold plunger until the aforesaid predetermined maximum is reached. Valve 69 is advantageously automatically operated, in this case by cam 71 on crank shaft 25. The precompression pressures exerted on the clay in the mold may be adjusted by adjusting the air pressure in storage tank 68. When cam 71 allows valve 69 to rise, the latter cuts off the air pressure supply and opens line 66 to exhaust, thereby releasing valve 62.

Still further modification of the pattern of pressures exerted by the toggle may be effected by varying (during different phases of each cycle) the pressures in air line 66, thereby changing (for predetermined phases of the cycle of toggle operations) the maximum pressure at which the mold plunger will yield. Ordinarily such elaboration of variation in pressure pattern will not be necessary. However, even when functioning to pre-

vent application of too high pressures, the hydraulic cylinder will modify the pressure pattern. For as soon as the predetermined maximum pressure is reached, the pressure pattern will be a straight line, without rise or fall for so long as the toggles are able to maintain the pressure.

Obviously the invention is not limited to the details of the illustrative apparatus since these may be variously modified. Moreover, it is not indispensable that all features of the invention be used conjointly since various features may be used to advantage in different combinations and sub-combinations.

Having described my invention, I claim:

1. In a press or the like for compressing materials of varying character, the combination comprising toggle arms for applying and releasing compression on the material, a link connecting said toggle arms, means for swinging said link to modify the operation of said toggle arms, and means for adjusting the character of compression to the material compressed by adjusting the angle of said link to said swinging means.

2. In a press or the like for compressing materials of varying character, the combination comprising toggle arms for applying and releasing compression on the material, a link between and connecting the toggle arms, an operating member connected with said link for operating said toggle arms, means for reciprocating and oscillating said member to swing and reciprocate said link, and means for adjusting the effective angle between said link and said operating member to adjust the character of compression to the material compressed.

3. In a press or the like for compressing materials of varying character, the combination comprising toggle arms for applying pressure, a link between said toggle arms, a connecting rod extending from said link for operating said toggle arms, and means for varying the angular relation between said connecting rod and said toggle arms for modifying the pattern of the pressures exerted by said toggle arms in accordance with the characteristics of the material.

4. In a press or the like for compressing materials of varying character, the combination comprising toggle arms for applying pressure, a link between said toggle arms, a connecting rod extending from said link for operating said toggle arms, and means including eccentric bushings in

the bearings between said link and the respective toggle arms to adjust the effective angle of said link relative to said toggle arms for varying the pressure pattern in accordance with the character of the material.

5. In a press or the like for compressing materials of varying characteristics, the combination comprising toggle arms, a link between said toggle arms, a connecting rod extending from said link for operating said toggle arms, a crank for operating said connecting rod, and an eccentric bushing in the bearing between said connecting rod and crank for adjusting the connecting rod relative to the dead center position of said toggle arms.

10 6. In a press or the like, the combination comprising toggle arms, a support against which said toggle arms operate, a hydraulic cylinder and piston on which said support is mounted, means for closing said cylinder against discharge below a predetermined pressure, and mechanism rendering said means inoperative during a portion 20 of the cycle to allow said support to yield under the pressure of said toggle arms.

25 7. In a press or the like, the combination comprising toggle arms, a movable support for assuming the thrust of said toggle arms, a hydraulic piston and cylinder carrying said support, means for applying a predetermined pressure in said cylinder, and pressure responsive means operative during a portion of the cycle to close said hydraulic cylinder to prevent substantial relative movement of piston and cylinder under the pressure of said toggle arms.

30 8. In a press or the like, the combination comprising toggle arms, a movable support for assuming the thrust of said toggle arms, a hydraulic piston and cylinder carrying said support, means for applying pneumatic pressure to the liquid in 40 said cylinder to allow said support to move under limited resilient pressures, and mechanism for cutting off said hydraulic cylinder during a portion of the cycle of operations to arrest further movement of said support, said mechanism including relief means to relieve said hydraulic cylinder when the operation of said toggle arms raises the hydraulic pressure in said cylinder to a predetermined maximum, thereby to limit the 45 maximum pressure exerted by said press.
